CLAIM

The ornamental design for stirrer or mixer for ice maker, as shown and described.

DESCRIPTION

FIG. 1 is a front view of a first embodiment of a stirrer or mixer for ice maker;

FIG. 2 is a rear view thereof;

FIG. 3 is a top view thereof;

FIG. 4 is a bottom view thereof;

FIG. 5 is a left side view thereof;

FIG. 6 is a right side view thereof;

FIG. 7 is a front top left perspective view thereof;

FIG. 8 is a rear top right perspective view thereof;

FIG. 9 is a front top right perspective view thereof; and,

FIG. 10 is a rear top left perspective view thereof.

Any broken lines in the figures illustrate portions of the stirrer or mixer for ice maker that form no part of the claimed design.
